UNITED STATES PATENT OFFICE.

MOSES G. FARMER, OF ELIOT, MAINE.

PRINTING-TELEGRAPH.

SPECIFICATION forming part of Letters Patent No. 460,572, dated October 6, 1891.

Application filed May 15, 1891. Serial No. 392,853. (No model.)

To all whom it may concern:

Be it known that I, MOSES G. FARMER, a citizen of the United States, residing at Eliot, in the county of York and State of Maine, have invented certain new and useful Improvements in Printing-Telegraphs, of which the following is a specification, reference being had to the drawings accompanying and forming a part of the same.

10 My present invention involves a novel application of the induction-coil or principle of induction to the operation of printing-telegraphs, according to which I have produced a simple and economical system or combination 15 of instruments for transmitting and printing dispatches which is better adapted for general use—such as along railroads and the like—than the more complicated systems which have been proposed, and which requires 20 on the part of the operators comparatively little previous knowledge or skill for its manipulation.

The invention is primarily an improvement upon a form of printing-telegraph which is 25 shown in a patent granted to me July 22, 1856, No. 15,373, but is applicable to others, being in the main distinguished by the following particular features. I employ an induction-coil with primary and secondary circuits. The secondary circuit is connected to the main line, over which induced currents only pass, and in the main line are polarized 30 relays for each instrument or station, that control the escapement or other means employed for rotating the type-wheel. The primary battery at each station, which is in operation only in transmitting, simply induces the currents that perform the work or control the action of the instruments.

40 By reference to the accompanying drawings the improvements which constitute my invention may be understood.

Figure 1 is a perspective view of the main operative parts of the receiving and printing mechanism of the invention. Fig. 2 is a diagrammatic illustration of the printing devices. Fig. 3 is a diagrammatic illustration of the parts comprising the invention connected by the proper circuit-wires.

50 At each station is a transmitting and receiving mechanism associated in one instrument. The former comprises, essentially, a series of

keys A B, alternately connected to the positive and negative poles of a primary battery C. With each key, as A, is associated as its anvil 55 a flexible or pivoted strip or bar F, and similarly associated with the keys B are the strips or bars G. The strips F G are normally in contact with bars or stops H, I, respectively, and are in 60 contact with their respective keys only when the latter are depressed. If the keys A are connected to the positive pole of the battery, the bars or stops H, with which the strips F are normally in contact, are connected to 65 the negative pole and the bar I to the positive pole. In conjunction with the keys I employ a sunflower or circuit disk K, composed of a circular series of metallic plates secured to an insulating-base, and over these a contact-arm or trailer K' is arranged to be rotated by any convenient mechanism such as is ordinarily used for this purpose—for example, a ratchet-wheel R and two magnets m m', that actuate pawls m'', that engage 75 with said ratchet-wheel.

The trailer K' is connected to the middle of the battery, and the contact-plates over which it sweeps are alternately connected with the positive and negative battery-poles 80 through the strips F G and bars H I, respectively. Therefore if no key be depressed the movement of the trailer around the disk will close one-half of the battery-cells and then the other, alternately, in opposite directions, 85 through the circuit of which the trailer forms a part. This fact is taken advantage of in making the alternately-reversed currents induced currents from a primary coil T in a secondary T' and causing these induced currents 90 to actuate a polarized relay W, that controls the two branches of a circuit containing a local battery t and the magnets m m'. A single current-impulse in either direction will therefore advance the trailer one step; but 95 the movements are so proportioned to the width of the plates L M that each single impulse moves the trailer from one plate L to another, as M.

The trailer K' is conveniently mounted on 100 a shaft K'', Fig. 1, on which or in gear with which is a type-wheel P and the ratchet or escapement wheel R, and it will be understood that when the proper relations be-

tween the numbers of the contact-plates L M, characters on the type-wheel, and teeth of the ratchet-wheel are observed the position of the trailer will determine what character 5 is brought to the printing-point.

S is the printing-magnet, and S' the printing lever or hammer operated thereby. The paper S'' is drawn by any proper devices for this purpose between the hammer and the 10 type-wheel, and when the magnet S is energized the paper is forced up against one of the letters on the type-wheel, which are inked by the inking-roller s.

The operation of the instrument is as follows: Assume the circuit connections to be 15 established by proper switches, which I have not deemed it necessary to show in detail in this case, to bring the line into condition for sending a dispatch, the trailer is moved onto 20 one of the plates of the disk K—say one of the plates L. The trailer being connected to the middle of the battery and each plate L to the negative or zinc pole of the same through a wire L', the strip or lever F, and the bar H, 25 a current will flow that induces a current in the coil T', and, according to its direction, shifts the polarized relay W onto one of its contacts and advances the trailer one step or onto the next plate M. By following the connections above described it will be seen that 30 this sends a current in the reverse direction through the primary and secondary coils and the polarized relay, and that thereby the tongue of the relay will be drawn over to the 35 opposite side and another impulse given to the trailer. If any key, as one of the keys B, be depressed to print the letter which it represents, the trailer and type-wheel revolve without interruption until the former, leaving 40 one of the plates L, moves onto the plate M, connected with the strip or lever G of the particular key depressed. Such strip or lever by the depression of its key is carried away from the bar I, by which it was normally 45 connected with the positive-battery pole; but by contact with its key it is now connected with the negative pole of the battery. The trailer, however, by its contact with the preceding plate L, has sent a current 50 to the negative pole, so that it now sends another current or impulse in the same direction. This does not move the relay W, and consequently the trailer and type-wheel come to a stop with the desired letter at the printing-point. This stoppage may be caused to 55 operate the printing-magnet by such a device as the pallet X, which I have shown in Fig. 2. This pallet rests upon a toothed wheel on the shaft of the type-wheel, as the escapement or 60 ratchet wheel R. While this pallet is borne upon one of the teeth of the wheel R it is raised out of contact with a fixed stop or pin p'. When, however, it falls between two of the teeth of the said wheel, it turns so far as 65 to bring its free end in contact with pin p', by which means a local circuit containing the printing-magnet S and a battery b' is closed.

During the normal operation and movement of the wheel R the pallet is not permitted to remain in contact with the pin p' for a sufficient length of time to energize the printing-magnet. 70

This apparatus in practice will be provided with some form of unison device; but as these are well known and generally used in instruments of this kind I have not illustrated any particular form herein. 75

The instrument at the distant station is the same as that shown. When not in use or when receiving, the circuit of the primary 80 battery C is broken and the relay W operated by the secondary impulses that come over the line from the transmitting-instrument.

It will be understood that in lieu of a single 85 divided battery two independent batteries may be used and that in other and similar immaterial respects the apparatus herein shown and described may be modified and varied without departure from the invention. 90

What I claim is—

1. The combination, in a printing-telegraph mechanism, with a primary battery, step-by-step mechanism adapted to reverse the current of the same, and keys for reversing the order of the connections of any part or branch 95 of the battery-circuit controlled by the step-by-step mechanism, of a secondary line-circuit in inductive relation to the primary circuit and a polarized magnet or relay therein for actuating the step-by-step mechanism, as 100 set forth.

2. In a printing-telegraph mechanism, the combination of a primary battery, a number of circuit branches corresponding to the characters to be printed and connected alternately to opposite poles of the battery, a trailer connected to the middle of the battery, and means for moving the same step by step over the terminal plates of the said branches, a primary coil in circuit with the trailer, a secondary line-circuit, a polarized magnet or relay 110 therein for actuating or controlling the step-by-step mechanism of the trailer, and character-keys for reversing the order of connection of each of the branches of the battery- 115 circuit, as set forth.

3. In a printing-telegraph mechanism, the combination, with a primary-battery circuit, the current in which is reversed by the movement of the operative parts of the instrument, of a secondary line-circuit in inductive relation to the same, a polarized magnet or relay 120 therein for actuating or controlling the action of the instrument, and circuit-reversing character-keys for arresting such action, as set 125 forth.

4. In a printing-telegraph instrument, the combination of a sunflower circuit-disk, branch circuits connected with the plates thereof and leading alternately from opposite 130 battery-poles, a trailer arranged to sweep over the plates of said disk and connected to the middle of the battery, character-keys adapted to reverse the connections of each of the

branch circuits, a secondary line-circuit in inductive relation to the trailer-circuit, and a relay therein for actuating or controlling the movement of the trailer.

5 5. The combination, with a step-by-step mechanism actuated or operated by induced currents in a line-circuit, of a primary battery and circuit adapted to be reversed by said step-by-step mechanism for inducing the currents in the secondary circuit, and character-

keys adapted to reverse the connections of any circuit or branch closed by the step-by-step mechanism, whereby two consecutive currents of the same direction may be produced in the primary circuit, as set forth.
